FIRING MECHANISM FOR A DEPTH CHARGE

Ronald O. Beach, Washington, D. C.

Application August 18, 1945, Serial No. 611,432

9 Claims. (Cl. 102—7)

(Granted under Title 35, U. S. Code (1952), sec. 266)

This invention relates generally to a firing mechanism for a depth charge. More specifically, the invention relates to a hydrostatically controlled switch adapted to close a firing circuit of the depth charge at a predetermined depth of submergence thereof.

An object of the present invention is to provide a new and improved depth charge firing mechanism in which a hydrostatically controlled switch operates at a pre-selected one of a plurality of depths to close the depth charge firing circuit.

Another object is the provision of a hydrostatically controlled switch for a depth charge firing mechanism which will not be prematurely operated by pressure waves such, for example, as pressure waves resulting from the detonation of an explosive charge within the vicinity of the depth charge.

Still another object is to provide a switch of the afore-described character which operates satisfactorily over a wide range of depths such, for example, as 50 to 1500 feet.

A further object is the provision of a new and improved hydrostatically controlled switch for a depth charge firing system which will render the system ineffective when the depth charge has descended to a predetermined depth in the event the depth charge is not fired during the descent thereof.

A still further object is the provision of a hydrostatically controlled switch which is rugged in construction and economical to manufacture.

Additional objects and advantages are those contained in and pertaining to the novel construction and arrangement of the elements of the device of the present invention, as will more clearly appear in the following description taken in connection with the accompanying drawings of which:

Fig. 1 is a top plan view of a depth charge pistol employing the device of the present invention;

Fig. 2 is a sectional view, with certain parts in elevation, taken substantially along the line 2—2 of Fig. 1;

Fig. 3 is a view similar to that of Fig. 1 with the top cover plate removed;

Fig. 4 is a vertical sectional view of the device of the present invention according to the preferred embodiment thereof;

Fig. 5 is a view in section taken along the line 5—5 of Fig. 4;

Fig. 6 is a view in section taken along the line 6—6 of Fig. 4;

Fig. 7 is an enlarged detailed view of the stepped contact member;

Fig. 8 is an enlarged detailed view taken along the line 8—8 of Fig. 4; and,

Fig. 9 illustrates in diagrammatic form a complete depth charge firing system including the hydrostatic switch of the present invention.

Referring now to the drawings wherein like characters of reference refer to like parts throughout the several views and more particularly to Figs. 4 through 8 inclusive, the numeral 10 designates a cylindrical member having

2

an axially disposed bore adapted to receive a tubular member 11. The aforesaid axially disposed bore extends through the cylindrical member 10, the uppermost portion of the bore having a reduced diameter such that the tubular member 11 engages the shoulder 12 in an abutting relation therewith.

A rod 13 composed of any suitable electrical conducting material such, for example, as brass is arranged to pass slideably through the aforesaid bore and tubular member 11. The cylindrical member 10 is provided with a circular flanged portion 14 within which is disposed a disk 15 preferably formed of Lucite, the rod 13 extending through a hole in the disk. Arranged within a recessed portion of the disk 15 is a resilient contact element 16, one end of the contact element being soldered to the upper extremity of rod 13 and the other end thereof being brought out through an ear-like portion 17 of the disk adapted to fit into a cut-away portion of the flange 14. The recessed portion of the disk also contains a quantity of a suitable insulating grease packed about the contact element 16 therein whereby the area of the protruding portion of the element only is exposed, thereby effectively reducing the electrical leakage due to electrolytic action which otherwise would exist between the contact element and its coating step member, hereinafter described. A rubber gasket 18 is provided between the disk 15 and the cylindrical member 10 in order to insure a water-tight connection therebetween. A metallic disk 19 is placed over the disk 15 with suitable insulating means 21 being arranged therebetween, and the assembly including disk 15, contact 16, gasket 18, disk 19 and insulating means 21 is secured to the flanged portion 14 of the cylindrical member as by crimping the flanged portion to the disk 19. In order to electrically insulate rod 13 from member 10 and the tubular member 11, a suitable piece of tubing 22 such, for example, as Saran tubing is disposed about the rod, the upper end of tubing 22 being provided with a circular lip 23 such that rod 13 will be sealed by the cold flow of gasket 18 when the aforesaid assembly is crimped to the flange 14 and immersed in a body of water.

A metallic bellows 24 is disposed about the cylindrical member 10 and the tubular member 11, the upper end of the bellows being centered by a shoulder 25 formed integrally on the member 10 and thereafter being soldered to the flange 14.

A substantially cylindrical casting 26 is provided having an axial bore for receiving the bellows 24, a shoulder 27 being provided therein for centering the lower end of the bellows which is soldered to the interior of the casting at 28. A bore of lesser diameter extends through the casting 26 through which passes rod 13 and tubing 22. The tubular member 11 is provided with a reduced end portion 29 for receiving a washer 31 adapted to support and center a stainless steel compression spring 32, a second washer 33 being provided to further center spring 32. The lower extremity of the cylindrical casting 26 is externally threaded to receive a stainless steel extension spring 34 having a greater number of turns and a greater degree of stiffness than the compression spring 32.

A set of three threaded telescopic adjusting members is provided in the device of the present invention and comprises an adjusting member 35 disposed about the tubular member 11 and arranged within the compression spring 32 for varying the depth at which the force acting upon compression spring 32 is transferred directly to the extension spring 34, and the compression spring thereafter is ineffectively to yieldably oppose movement of the contact assembly. The springs are so adjusted that the transfer preferably is arranged to occur at a depth other than the depths at which the contact element engages the step member for the reason that contacting thereof at the proper depth is difficult when the contacting occurs dur-

ing the transfer period. The adjusting member 36 is disposed about the member 35 and is adapted to engage the spring centering washer 33 in an abutting relation therewith to preload the compression spring, the spring rate of the extension spring being varied by the adjusting member 37 which varies the number of active turns therein. The purpose of the aforesaid adjusting members will appear in greater detail hereinafter.

The casting 26 is provided with a recessed flanged portion 38 within which is mounted a cover 39 securely clamped by a ring member 41 which is crimped to the flanged portion of the casting, the cover 39 and member 41 each being composed of a material upon which ice coatings will not form such, for example, as Lucite. The cover 39 is provided with a lower reduced end portion about which a slip ring 42 composed of any suitable electrical conducting material is arranged, electrical connection to the slip ring being provided by a contact element 43 engaging the slip ring and extending exteriorly of the ring 41, a suitable insulating ring 40 being disposed intermediate the cover 39 and flanged portion 38 of casting 26.

Arranged about the inner circumference of the cover 39 is a step member 44 composed of a suitable conducting material and conveniently formed into the shape illustrated in any convenient manner, preferably by punching the member from a thin strip or sheet of material. The step member is soldered to the slip ring by means of ears 45 formed integrally with the step member, the member 44 being insulated from bellows 24 by an insulating sleeve 50. Fig. 7 is a detailed view of the step member 44 which is provided with a plurality of indentations or steps adapted to be engaged by the contact element 16 selectively in accordance with a predetermined depth selection as will appear more clearly as the description proceeds.

The instant device is adapted for use with a depth charge pistol of the type shown in Figs. 1 through 3, which pistol is described and claimed in the copending application of R. M. Cate et al. for Depth Charge Arming Device, Serial No. 596,065, filed May 26, 1945. The aforesaid pistol will now briefly be described and reference is made to the aforesaid application for a more detailed description thereof.

An electroresponsive detonator assembly 46 is arranged in predetermined spaced relation with respect to a booster charge 47, the detonator assembly being adapted to be rotated into operative relation with the booster charge by a dual bellows arrangement under pressure of the surrounding water. The aforesaid bellows arrangement comprises the fluid filled bellows 48 and 49 separated by a partition 51 having an orifice 52 therein such that flow of fluid from bellows 48 to bellows 49 is restricted, thus preventing substantial movement of the bellows 48 and 49 when external shocks such, for example, as countermine shocks or the blow received in striking the water is received by the bellows. Flow of fluid between the bellows, however, in response to pressure gradually applied to bellows 48 by the surrounding water as the associated depth charge descends through the water is sufficient to cause displacement of the bellows.

The bellows 48 and 49 are secured to the partition 51 and a plunger 53 is secured to the free ends of the bellows and is adapted to pass through the partition slideably. The plunger 53 is connected at its inner end to a linkage generally indicated by the numeral 54 which in turn is operatively secured to the detonator assembly 46 such that the detonator assembly is rotated into operative relation with the booster charge 47 when a sufficient displacement of the dual bellows arrangement is produced. A plurality of spring members 55 are employed to control the depth at which the rotation of the detonator assembly is completed.

A plurality of electrical switches are also employed in the pistol and are adapted to be operated in predetermined sequential order to complete certain electrical circuits comprising the firing control system of a depth charge, one of

such switches comprising contacts 56 and 57 and contacts 58 and 59, Fig. 9, adapted to close the detonator circuit when the detonator assembly is rotated into operative relation with the booster charge. The remaining switches 5 comprising contacts 61 and 62 and contacts 63 and 64 respectively, Fig. 9, are hydrostatically operated and are utilized to apply static operating potentials from a source of power to the electron discharge devices included in the firing control system described in the aforesaid application.

The hydrostatically controlled switch of the instant invention is supported on the cup-shaped member 65 of the aforescribed arming device and secured thereto by a nut 66 disposed about the externally threaded portion of the casting 26, suitable gasket means 67 being arranged between the flanged portion of the casting and the cup-shaped member 65 to insure a water-tight connection therebetween. It will be noted that an orientating pin 68 is secured to the flanged portion of the casting, a hole being cut in the cup-shaped member 65 for receiving the orientating pin.

An indexing device generally indicated by the numeral 69 is provided for the switch and comprises a substantially cylindrical shaft 71 having a flat surface extending the length thereof, the cover 39 having a hole cut therein for receiving the shaft 71. The cover 39 and shaft 71 are adapted to be rotated by turning a knob 72, which knob has an arm 73 extending radially therefrom. A disc 74 and bearing member 75 rotate with the shaft and knob, the disc 74 having affixed thereon suitable indicia, Fig. 1, for indicating a plurality of depths of submergence corresponding respectively to the plurality of indentations formed on the step member 44, the bearing member 75 being disposed within a hole in the cover 76 of the pistol. A spring member 77 is affixed to the bearing member 75 as by swaging and is provided with oppositely disposed ears 78 adapted to engage a plurality of indentations 79 circumferentially arranged in predetermined spaced relation on the inner surface of the pistol cover 76, the spring member also being adapted to preload a gasket 81 disposed intermediate the disc 74 and cover 76.

A conductor 80 is soldered to the lower extremity of rod 13 to establish an electrical connection to the detonator 46 while another conductor 82 is soldered to the contact element 43 to establish electrical connection between the switch and a sea cell 83, the sea cell being supported on a bracket 84 secured to the post member 85 by a nut 86. The sea cell 83 may be of any suitable type adapted to generate an electric potential when immersed in sea water. A conductor 87 extends from the positive terminal of the cell 83 to a terminal 88 affixed to a horizontal strip of insulating material 89, the strip 89, in turn, being supported on the post member 91 by a nut 92. A second terminal 93 is affixed to the strip 89 and is adapted to receive conductor 82, a suitable strip 55 of conducting material 94 being connected between the terminals to maintain electrical connection therebetween.

The operation of the switch of the present invention will now be described with reference to Fig. 4 of the drawings. The cylindrical member 10 and contact element 16 carried thereby and the tubular member 11 comprise a piston adapted to be moved inwardly under pressure of the surrounding water, the compression spring 32 and extension spring 34 acting in parallel and serving to yieldably oppose such inward movement, thereby to control the displacement of the members 10 and 11 in accordance with the value of water pressure acting thereon. As the water pressure increases, the tubular member 11 causes the washer 31 to move into engagement with the adjusting member 35 whereupon the compression spring 32 is rendered ineffective to further oppose the inward movement of members 10 and 11 and the force acting thereon is transferred to the extension spring 34 which further controls the displacement of members 10 and 11 in accordance with the value of water pressure. It will be understood, at this point, that for a given depth of sub-

merion the actual pressure exerted on the springs 32 and 34 is less than the theoretical pressure exerted thereon since the effective area of bellows 24 decreases progressively as the switch descends through the water, such condition becoming more clearly manifest at greater depths of submergence. In order to maintain the linearity desired in depth selecting for firing at greater depths, the indentations on the member 44 are formed non-linearly, the spring rates of each of the springs being linear.

The adjusting members 36 and 37 are provided in order that the opposing force exerted by the springs 32 and 34 respectively may be varied to calibrate the displacement of the contact element 16 in accordance with the water pressure at a predetermined depth. The contact element 16 is adapted to engage one of the plurality of indentations of the step member 44 selectively in accordance with the depth preselected by the indexing device 69, such preselection being accomplished by rotating the knob 72 until the numeral on the disc 74 indicating the desired depth alines with the arrow 95 formed on the cover 76, thus placing the corresponding indentation on the member 44 directly beneath the contact element 16.

Let it be assumed, by way of example, that the hydrostatic switch of the present invention is employed in an arming device of the type described in the aforesaid application of R. M. Cate et al. and that the arming device is utilized in a depth charge having a firing circuit similar to that described and claimed in the co-pending application of Harry H. Hall et al. for Means for Firing an Explosive Charge, Serial No. 520,074, filed January 28, 1944, which firing circuit is shown schematically in Fig. 9 and comprises a signal pickup device which controls the operation of a suitable amplifier. The amplifier, in turn, controls the operation of a firing relay 96 which, when operated, completes an electrical circuit from a battery 97 to the detonator 46, thereby exploding the depth charge. In such case, the hydrostatically controlled firing system provided by the switch and sea cell 83 supplements the influence firing system controlled by the proximity of a submarine in order to insure the detonation of the depth charge in the event that the depth charge does not pass sufficiently close to the target submarine to actuate the influence firing system. Such an arrangement is especially desirable when a convoy of ships is under attack by enemy submarines since the positive detonation of depth charges will, at least, drive the attacking submarines from the vicinity.

Let it be assumed, for the purpose of description, that a depth charge employing both the influence and hydrostatic firing systems is launched from a surface vessel and directed at a submarine. Let it further be assumed that before the launching, the hydrostatic system is adjusted to fire at a depth of 300 feet by rotating knob 72 until the number 300 on disc 74 alines with arrow 95, thereby placing the indentation marked 300 on the step member 44, Fig. 7, directly beneath the contact element 16.

As the depth charge descends through the water, hydrostatic pressure causes contacts 61 and 62 to close as well as contacts 63 and 64, thereby applying static operating potentials to the electron discharge devices included in the influence firing system. The hydrostatic pressure also causes a lead diaphragm 100, formed integrally with the container for the sea cell, to be ruptured when the pressure reaches a predetermined value, thereby admitting the sea water to the cell to activate the same. Thus, by reason of this arrangement a safety feature is provided in that no potential is applied to the detonator before the depth charge is immersed in water although the detonator is otherwise fully armed as by inadvertence or accident. As the depth charge continues to descend through the water, the detonator 46 is rotated into operative relation with the booster charge 47 by the bellows 48 and 49 under pressure of the surrounding water.

When the detonator moves into the armed position, contact 56 moves into engagement with contact 57 and contact 58 moves into engagement with contact 59 whereby the depth charge is electrically armed.

If the path of descent of the depth charge is sufficiently close to the submarine and if the depth charge moves within the influence zone of the submarine before a depth of 300 feet is reached, the influence system operates to close relay 96 and complete a circuit from battery 97 to the detonator 46 to explode the charge. In the event, however, that the path of descent of the depth charge is not sufficiently close to the submarine to actuate the influence firing system, the hydrostatically controlled system will be caused to operate in the following manner. As the depth charge descends through the water, water seeps into the interior of the switch through a hole 98 in the cover and through the minute space between the cover and ring member, the resulting water pressure reacting upon the piston assembly comprising contact 16, cylindrical member 10 and the tubular member 11 to cause inward movement thereof against the compression spring 32.

The aforesaid assembly continues to move inwardly as the depth charge sinks deeper and the water pressure increases, with the spring 32 providing substantially all of the force opposing such motion until a depth of 200 feet is reached. When this occurs, the washer 31 engages the adjusting member 35 and spring 32 is cut out, whereupon, the extension spring 34 alone exerts the force tending to oppose the inward motion of the assembly. When the depth charge sinks to a depth of 300 feet, the contact element 16 will have traveled the distance necessary to engage the 300 ft. step on member 44 to complete a circuit from the sea cell 83, through the contact 43, slip ring 42, step member 44, contact 16, rod 13, conductor 80 and detonator 46, thus exploding the depth charge.

Under certain submarine attacking conditions, it may be desirable to cause the depth charge to become active only by the proximity of the submarine, in which case the hydrostatically controlled firing system must be rendered ineffective before the launching of the depth charge. Accordingly, the step member 44, when assembled within the ring member 39, does not form a closed cylinder but provides a slot 99 through which contact 16 passes when the knob 72 is adjusted to aline the letters IN formed on disc 74 with the arrow 95. With the step member so adjusted, contact 16 engages the cover 39 as the contact is moved inwardly under pressure of the surrounding water thereby preventing the completion of a circuit from the sea cell 83 to the detonator 46.

Whereas, in the foregoing it was assumed that the switch of the instant invention is to be utilized in connection with influence firing systems for depth charges to provide selective firing thereof, it will, of course, be understood that the switch may be used singularly in a depth charge to provide a hydrostatically controlled firing system, in which case the firing system comprises the switch of the present invention, sea cell 83 and the detonator assembly 46.

In the event that a sudden increase in pressure of the surrounding water is produced during the descent of the depth charge by the detonation of a neighboring charge, for example, the flow of water into the switch through hole 98 and the minute space between the cover 39 and ring member 41 is restricted or damped whereby the piston is prevented from moving inwardly in response to such sudden increases in water pressure.

Moreover, it will be noted that the contact element 16 is adapted to engage the interior of casting 26 if the depth charge descends beyond 1500 feet without being fired. When this occurs, the detonator becomes short-circuited and the depth charge is sterilized.

From the foregoing it should now be apparent that a hydrostatically controlled switch has been provided which

is well adapted to fulfill the aforesaid objects of the invention.

While the invention has been described in particularity with reference to an example thereof which gives satisfactory results, it readily will be apparent to those skilled in the art to which the invention appertains, after understanding the invention, that further embodiments, modifications and changes may be made therein without departing from the spirit and scope thereof as defined by the claims appended hereto.

The present invention may be manufactured and used by or for the Government of the United States of America for governmental purposes without payment of any royalties thereon or therefor.

What is claimed as new and desired to be secured by Letters Patent of the United States is:

1. A pressure responsive device of the character disclosed comprising, in combination, a piston movable under hydrostatic pressure, a contact element carried by said piston, settable contact means including a plurality of steps arranged in spaced relation with respect to said contact element and adapted to be engaged thereby selectively in accordance with the setting of the contact means when hydrostatic pressure sufficient to move said piston is applied thereto, means for yieldably opposing the movement of said piston thereby to cause said element to engage said steps selectively at preselected depths of submergence respectively corresponding thereto, and means including said contact means for preselecting and setting one of said steps thereof for mutual engagement with said element.

2. A pressure responsive device of the character disclosed comprising, in combination, a piston movable under hydrostatic pressure, a contact element carried by said piston, settable contact means including a plurality of steps arranged in spaced relation with respect to said contact element and adapted to be engaged thereby selectively in accordance with the setting of the contact means when hydrostatic pressure sufficient to move said piston is applied thereto, means for yieldably opposing the movement of said piston thereby to cause said element to engage said steps at substantially preselected depths of submergence respectively corresponding thereto, adjusting means for varying the operation of said opposing means thereby to cause said elements and steps to mutually engage at depths which closely correspond to said preselected depths, and means including said contact means for preselecting any one of said steps for mutual engagement with said element.

3. A switch adapted to be immersed in a body of water and comprising, in combination, a member adapted to be moved along an axis when hydrostatic pressure is applied thereto, a contact element carried by said member and arranged transversely of said axis, means for controlling the distance traveled by said member in accordance with the depth of submersion of said switch, contact means rotatable about said axis and having a plurality of steps circumferentially disposed about the axis corresponding respectively to a plurality of depths of submersion, and means for rotating said contact means to align one of said plurality of steps with said contact element thereby to preselect one of said plurality of depths of submersion at which said contacts will mutually engage.

4. A switch adapted to be immersed in a body of water and comprising, in combination, a piston movable under hydrostatic pressure, a contact element carried by said piston, settable contact means having a plurality of steps arranged in spaced relation with respect to said contact element and adapted to be engaged thereby selectively in accordance with the setting of the contact means as said switch descends through the water, means including said contact means for preselecting one of said steps for mutual engagement with said element, means for yieldably opposing the movement of said piston thereby to

cause said element and steps to mutually engage at a plurality of depths of submergence respectively corresponding thereto, said opposing means comprising a first resilient means for opposing the movement of said plunger over a predetermined range of depths and a second resilient means for opposing the movement of the plunger over a different predetermined range of depths, and means for coupling said first and second resilient means in such a manner to render the first resilient means ineffective over said different predetermined range of depths.

5. In a firing circuit for a depth charge adapted to be armed as the depth charge descends through a body of water, the combination of hydrostatic means for arming said circuit, an electroresponsive detonator included in said circuit, means connected in the firing circuit and effective when immersed in salt water for generating electrical energy for firing said detonator when the circuit is completed, a water-tight housing for said generating means, said housing having a diaphragm formed integrally therewith and adapted to be ruptured by the pressure of the surrounding water thereby to admit water to the generating means, and hydrostatically controlled means for completing said firing circuit after the circuit has been armed.

6. A pressure responsive device of the character disclosed comprising, in combination, a piston movable under hydrostatic pressure, a contact element carried by said piston, a settable contact means including a plurality of steps arranged in spaced relation with respect to said contact element and adapted to be engaged thereby selectively in accordance with the setting of the contact means when hydrostatic pressure sufficient to move said piston is applied thereto, means for effectively reducing electrical leakage between said contact element and said contact means caused by electrolytic action therebetween, means for yieldably opposing the movement of said piston thereby to cause said element and steps to mutually engage at preselected depths of submergence respectively corresponding thereto, and means including said contact means for preselecting and setting one of said steps for mutual engagement with said element.

7. In a firing mechanism for a depth charge, a piston in communication with the surrounding water and arranged to be moved along its axis in response to hydrostatic pressure thereon, means for yieldably opposing movement of the piston whereby the piston is moved variably in accordance with the water pressure thereon, a contact element carried by said piston for movement therewith, an electroresponsive detonator connected to said contact element, a settable stepped conductor spirally disposed about said piston and rotatable about the axis thereof into any one of a plurality of different initially spaced positions with respect to said contact element for engagement therewith at any one of a plurality of depths of submergence corresponding respectively to said plurality of different positions, and a source of energy connected to said stepped conductor and to said detonator whereby the detonator is fired by energy received therefrom as the contact element engages said conductor.

8. A pressure responsive device comprising in combination, means movable in response to hydrostatic pressure, a contact element carried by said movable means, an annular contact settable at will to different settings, a plurality of steps on said annular contact for engagement with said contact element as the movable means is moved from an initial position to a selected position, and means for moving said annular contact to a selected setting.

9. A switch for a depth charge adapted to be immersed in a body of water comprising, in combination, means movable in response to a predetermined hydrostatic pressure, a contact element carried by said pressure responsive means, an annular contact rotatably supported on said switch and having a plurality of steps corresponding to a plurality of depths of submersion, and actuating means

9

secured to said annular contact for selecting one of said plurality of depths of submersion at which said contacts will engage.
